OUTLET BRAZE ASSEMBLY FOR AUTOMOTIVE AIR CONDITIONING SYSTEMS

Arthur S. Kish, Lyndhurst, Ohio, assignor to Murray
Corporation, Cockeysville, Md.

Filed Apr. 23, 1973, Ser. No. 353,473

Term of patent 14 years

Int. Cl. D23—01

U.S. Cl. D23—43

Fig. 1

Fig. 2

Fig. 3

Fig. 4

Fig. 5

FIG. 1 is a top plan view of an outlet braze assembly for automotive air conditioning systems embodying my new design;

FIG. 2 is a front elevational view of the assembly; FIG. 3 is a cross-sectional view, taken on the line 3—3 of FIG. 1;

FIG. 4 is a bottom plan view of the assembly, and

FIG. 5 is an end elevational view of the assembly, as viewed from the right end of FIG. 2.

I claim:

The ornamental design for an outlet braze assembly for automotive air conditioning systems, substantially as shown.
